CLAIM

The ornamental design for a folding stool, as shown and described.

DESCRIPTION

FIG. 1 is a top, front, left-side perspective view of a folding stool showing my new design;

FIG. 2 is a bottom, front, left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a top, front, left-side perspective view of FIG. 1, shown with the legs in an extended configuration; and,

FIG. 10 is a top, front, left-side perspective view of FIG. 1, in a folded configuration.

The broken lines shown in the drawings depict portions of the folding stool and form no part of the claimed design.

1 Claim, 9 Drawing Sheets
